UNITED STATES PATENT OFFICE.

ALBERT C. SMITH, OF BOULDER, COLORADO.

DESIGN FOR A BRACKET FOR CURTAIN-POLES AND SHADE-ROLLERS.

SPECIFICATION forming part of Design No. 28,858, dated June 14, 1898.

Application filed May 14, 1898. Serial No. 680,746. Term of patent 14 years.

To all whom it may concern:

Be it known that I, ALBERT C. SMITH, a citizen of the United States, residing at Boulder, in the county of Boulder and State of Colorado, have invented and produced a new and original Design for Curtain-Pole and Shade-Roller Brackets, of which the following is a specification, reference being had to the accompanying drawing, forming a part thereof, of, in which the figure is a perspective view illustrative of my design.

As shown in the drawing, the leading or characteristic feature of the design is the formation in the upper bar of two depressions, one being located near the outer end of said bar and segmental in form, and the other at a point intermediate of the ends of said bar, rectangular or circular in form, and the formation upon the lower bar of an upwardly-extending arm, which is bent at an intermediate point, forming an eye through which the upper bar passes, is bent down upon itself, and formed with a terminal eye or loop which lies in a plane at right angles to the plane of the two bars.

The upper bar 1 is gimlet-pointed at one end and provided with large screw-threads 2, adjacent thereto, has a segmental depression 3 therein at a point near its opposite end, and

an intermediate depression 4, whose side 30 walls are parallel or circular in form. Formed integral with the upper bar is the lower bar 5, which leads from the outer end of the bar 1 along a line substantially parallel to that portion of the bar 1 in which the depression 35 3 is formed, is bent at the point 6 between the center and the inner end of the depression 3, and continued rearwardly toward the opposite end of the bar 1, as clearly shown. The rear or inner end of the bar 5 has extending upwardly from it at right angles to the bar 1 an arm 7, which is bent at a point intermediate of its ends, forming a loop or eye 8, through which the bar 1 passes, and has a terminal loop or eye 9, which lies in a plane 45 at right angles to the bars 1 and 5.

Having now described my invention, what I claim is—

The design for a curtain-pole and shade-roller bracket, substantially as herein shown 50 and described.

In testimony whereof I affix my signature in the presence of two witnesses.

ALBERT C. SMITH.
